LIFT PLUG VALVE

Ferdinand Hinrichs, Kenosha, Wis., assignor to
 Tri-Clover Machine Co., Kenosha, Wis., a corporation of Wisconsin

Application February 7, 1951, Serial No. 209,747

3 Claims. (Cl. 251—97)

1

This invention relates to improvements in lift plug valves.

Plug valves of a type which employ a tapered valve member rotatable in a tapered bore have many features which make them particularly desirable for use in controlling the flow of fluid in pasteurizing equipment or other apparatus where a high degree of sanitation is required. An objectionable feature of this type of valve, however, is the fact that the plug member when seated in the bore is hard to rotate unless it is first lifted slightly from its seat.

Various devices have been heretofore proposed for dislodging the plug from its seat prior to rotation. The prior devices have not been satisfactory for a number of reasons. Certain of the prior devices have embodied cam surfaces which are difficult and expensive to form. Others have embodied too many parts to be practical, or have embodied interior threading, shoulders, or recesses which are objectionable because they provide places in which food particles can collect and from which the removal of said particles is difficult. Another objection to the prior valves is that squirting of fluid from around the dislodged plug results when the plug is lifted off of its seat. This squirting of fluid is obviously highly objectionable from a sanitary standpoint. It has been found that plugs having a standard taper can be freely rotated without any squirting of fluid (such as milk) from the valve if the plug is lifted not substantially more than .003 inch.

With the above in mind it is a general object of the present invention to provide an improved lift plug valve which is so constructed that upon movement of the valve handle the valve plug will first be lifted sufficiently to dislodge the same, the amount of lift, however, being insufficient to cause squirting of fluid.

A further object of the invention is to provide an improved lift plug valve of the class described wherein the lifting of the valve plug is accomplished by cam surfaces which are inexpensively formed.

A further object of the invention is to provide an improved lift plug valve of the class described wherein the plug lifting cam surfaces are circular in conformation and therefore require a minimum amount of movement of the valve handle in order to produce the desired lifting of the plug, said circular cam surfaces at the same time having a limited plug lifting range to eliminate the possibility of fluid squirting.

A further object of the invention is to provide an improved lift plug valve of the class described which, due to the elimination of fluid squirting,

2

does not require a cover and which therefore is provided with a bearing plate for carrying the cam surfaces and handle, said bearing plate having only limited frictional contact with the valve body.

A further object of the invention is to provide an improved lift plug valve of the class described which is formed of a relatively small number of parts all of which can be easily and quickly disassembled and cleaned; to provide a valve which is strong and durable; and to provide a valve which is otherwise well adapted for the purposes described.

With the above and other objects in view, the invention consists of the improved lift plug valve, and all of its parts and combinations, as set forth in the claims, and all equivalents thereof.

In the drawing accompanying and forming a part of this specification, wherein is shown one complete embodiment of the preferred form of the invention, and wherein like characters of reference indicate the same parts in all of the views:

Fig. 1 is a side elevational view of the improved valve, part being broken away and shown in section;

Fig. 2 is a fragmentary vertical sectional view taken approximately along the line 2—2 of Fig. 1;

Fig. 3 is a fragmentary plan view of the improved valve; and

Fig. 4 is a fragmentary side elevational view of the improved valve showing the parts in plug lifting position.

Referring more particularly to the drawing, the numeral 10 indicates a valve body having opposed inlet and outlet connections 11 and 12 and having a tapered bore 13 in which is positioned a tapered plug 14. The plug 14 may be urged into seated position in the bore 13 by means including a stud 15 projecting axially from the bottom of the plug 14, said stud having a nut 16 threaded thereon. A dished spring washer 17 may have its periphery in engagement with the bottom of the valve body 10 with its central portion in abutment with the nut 16 as shown.

Projecting axially from the large end of the plug 14 is an integral stem 18 which is formed adjacent its upper end with a diametrically extending bore 19. Positioned on the valve body 10 adjacent the large end of the bore 13 is a generally T-shaped bearing plate 20 having arm portions 21, 22 and 23 which overlap the margins of the bore 13 and which are slidable on the upper end of the valve body. The bearing plate 20 is formed with a central aperture 24 through which the stem 18 rotatably and axially slidably pro-

jects. Formed on and projecting laterally from the arm 22 of the bearing plate 20 is a handle 25.

Formed on the bearing plate 20 adjacent diametrically opposite side portions of the stem 18 is a pair of upstanding bosses 26 and 27. The bosses 26 and 27 are formed respectively with circular apertures 28 and 29 having a common axis which preferably extends diametrically of the stem 18. A cylindrical pin 30 having an outside diameter substantially equal to the diameter of the stem bore 19 and having an enlarged head 31, is carried in the stem bore and projects through the circular apertures 28 and 29 as shown in Fig. 2. The pin 30 may be provided with a conventional means such as the ball 32 for holding said pin in the position shown.

The relative positions of the apertures 28 and 29 and the stem bore 19 are such that when the plug 14 is seated in the bore 13, the pin 30 rests on the lowermost wall portions of the apertures 28 and 29, as shown in Figs. 1 and 2. The ratio of the diameter of the apertures 28 and 29 to the diameter of the pin 30 may vary in accordance with design requirements. Most satisfactory results have been obtained when the ratio of the diameter of the pin to the diameter of the boss apertures is on the order of 3 to 5.

In operation, movement of the handle 25 in either direction causes initial rotation of the bearing plate 20 about and relative to the stem 18. This relative movement causes the pin 30 to be lifted by the cam surfaces which are provided by the apertures 28 and 29, and the plug 14 is, of course, lifted simultaneously with the pin. Fig. 4 shows the parts in plug lifting position, and a comparison of the space (a) of Fig. 1 and (b) of Fig. 4 indicates the extent to which the plug 14 is lifted in Fig. 4. The use of the circular cam surfaces formed by the apertures 28 and 29 and the preferred relationship between the diameters of said apertures and that of the pin 19 is such as to cause lifting of the valve plug 14 not substantially more than .003 of an inch. Other relationships may, however, be employed to suit particular conditions. Further movement of the handle 25 causes rotation of the lifted plug without additional lifting. When a plug of the type shown in the drawing has been lifted .003 inch it is freely rotatable, and there is no squirting of fluid from around said plug as said plug is rotated. The lifting of the plug begins immediately upon movement of the handle 25 in either direction, thereby providing quick operation of the valve.

The improved T-shaped bearing plate causes substantially less friction than conventional rotatable cover plates which are in frictional engagement with the valve body around the entire periphery thereof. The cam surfaces formed by the apertures 28 and 29 not only provide a unique limited lifting effect, but in addition the construction is advantageous because the apertures are inexpensively formed by use of conventional production drilling equipment, there being no special machinery required therefor. The improved valve is especially well adapted for use in sanitary equipment, not only because of the small number of parts to be disassembled and cleaned, but also because of the fact that squirting of fluid from around the valve plug is eliminated.

Various changes and modifications may be made without departing from the spirit of the invention, and all of such changes are contemplated, as may come within the scope of the claims.

What I claim is:

1. In a lift plug valve: a valve body formed with a tapered bore; a tapered plug cooperable with said tapered bore; a stem projecting axially from the large end of said plug; a bearing plate rotatably positioned on the valve body over the large end of the tapered bore; a handle for said bearing plate, said plate being formed with a central aperture through which the plug stem rotatably projects; a pair of upstanding bosses formed on said bearing plate on opposite sides of said plug stem, said bosses being formed with coaxial circular bores extending transversely therethrough; and a transverse pin carried by said stem and projecting substantially diametrically thereof into the circular bores of said bosses, the ends of said pin being circular in cross-section and having a diameter larger than the radius of said bores and substantially smaller than the diameter of said bores, whereby said circular bores present a cam surface of increasing slope to the pin ends.

2. In a lift plug valve: a valve body formed with a tapered bore; a tapered plug cooperable with said tapered bore; a stem projecting axially from the large end of said plug; a bearing plate rotatably positioned on the valve body over the large end of the tapered bore; a handle for said bearing plate, said plate being formed with a central aperture through which the plug stem rotatably projects; a pair of upstanding bosses formed on said bearing plate on opposite sides of said plug stem, said bosses being formed with coaxial circular bores extending transversely therethrough, and a transverse cylindrical pin carried by said stem and projecting substantially diametrically thereof into the bores of said bosses, the ratio of the diameter of said pin to the diameter of said bores being approximately three to five, whereby said circular bores present a cam surface of increasing slope to the pin ends.

3. In a lift plug valve: a valve body formed with a tapered bore; a tapered plug cooperable with said tapered bore; a stem projecting axially from the large end of said plug; a bearing plate rotatably positioned on the valve body over the large end of the tapered bore; a handle for said bearing plate, said plate being formed with a central aperture through which the plug stem rotatably projects; a pair of upstanding bosses formed on said bearing plate on opposite sides of said plug stem, said bosses having coaxial circular bores extending transversely therethrough; and a transverse pin carried by said stem and projecting substantially diametrically thereof into the circular bores of said bosses, the ends of said pin being circular in cross-section and having a diameter substantially smaller than the diameter of said bores, whereby said circular bores present a cam surface of increasing slope to the pin ends.

FERDINAND HINRICHES.
